UNITED STATES PATENT OFFICE.

ELZA E. WIFORD, OF SIDNEY, OHIO.

AUTOMATIC STOP FOR TALKING MACHINES.

1,404,078.

Specification of Letters Patent. Patented Jan. 17, 1922.

Application filed May 10, 1920. Serial No. 380,205.

To all whom it may concern:

Be it known that I, ELZA E. WIFORD, a citizen of the United States, residing at Sidney, in the county of Shelby and State of Ohio, have invented new and useful Improvements in Automatic Stops for Talking Machines, of which the following is a specification.

This invention relates to automatic stops for talking machines, and comprehends a construction which can be accurately set in a minimum of time, the construction being simple but yet positive of operation for the purpose intended.

The nature and advantages of the invention will be better understood when the following detail description is taken in connection with the accompanying drawings, the invention residing in the construction, combination and arrangement of parts as claimed.

In the drawings forming part of this application like numerals of reference indicate similar parts in the several views, and wherein:

Figure 1 is a plan view of a talking machine showing the turn table by dotted lines, and the automatic stop mechanism arranged therebeneath.

Figure 2 is a fragmentary view showing the set position of the stop mechanism.

Figure 3 is a sectional view taken on line 3-3 of Figure 1.

Figure 4 is a detail view of the trip element.

Referring to the drawings in detail, A indicates the turn-table of the machine, B the tone arm, and C the reproducer.

The automatic stop mechanism forming the subject matter of my invention comprises a base plate indicated at 10 and adapted to be secured to the machine in any suitable manner, but beneath the turn-table A. Pivoted as at 11 upon the base plate 10 is the combined starting and setting lever 12, this lever being manually operable in setting the mechanism, and for which purpose it projects an appreciable distance beyond the periphery of the turn-table A. This lever is formed to provide a segmental end portion 13 which reposes upon the base plate 10, and this portion cooperates with a pivoted latch element 14 for holding the mechanism in set position. A brake of usual construction indicated at 15 is mounted upon

the lever 12 at points where it normally contacts the flange of the turntable A as clearly illustrated in Figure 1. The latch element 14 is curved to correspond with the curvature of the outer edge of the segmental portion of the lever 12, the element 14 being pivoted upon the base plate 10 as at 16. A coiled spring 17 connects the latch element with the segmental portion of the lever 12, this spring functioning to hold the parts operatively associated. The latch element 14 is provided with a tooth or lug 18 which is engaged by a similar tooth or lug 19 formed on the segmental portion of the lever 12, when the parts are in set position.

Pivoted upon the free extremity of the latch element 14, is a finger 20 having a cam like portion 21 for the purpose to be presently described. The finger 20 is normally positioned in the manner shown in Figure 1, and is moved to its set position through the instrumentality of a pin 22 carried by the segmental portion of the lever 12. A trip element for the finger 20 is indicated at 24 and is secured to the tone arm B. The trip element is of the configuration illustrated in Figure 4, and includes a depending portion 24' which is adapted to contact the finger 20 to operate the automatic stop for the machine.

Normally, the parts are arranged in the manner shown in Figure 1, and subsequent to the placing of a record upon the turntable, the needle of the reproducer is arranged in the innermost groove of the record. This of course swings the tone arm upon its pivot and positions the trip element 24 with respect to the center of the record. The combined starting and setting lever 12 is now moved upon its pivot in a direction to space the brake from the flange of the turntable, thus permitting the turntable to rotate. When the lever 12 is moved in this direction, the pin 22 is moved into engagement with the cam-like portion 21 of the finger 20, moving the finger upon its pivot into contacting engagement with the trip element 24. This constitutes the set position of the finger 20. However, during the movement of the finger to a set position, the latch element 14 is also swung upon its pivot away from the segmental portion of the lever 12, thus allowing the tooth 18 to pass beyond the tooth 19 of the latch element, and also placing the spring connecting these parts under tension.

Before the lever 12 is released, the reproducer is moved upon the periphery of the record and the needle placed in the outermost sound groove of the record. Upon release of the lever 12, the segmental portion of the lever and the latch element 14 are drawn toward each other through the instrumentality of the spring connecting the same, and consequently the teeth 18 and 19 respectively contact each other and thereby hold the mechanism in a set position and the brake spaced from the flange of the turntable. As the needle moves toward the center of the record, the trip 24 on its tone arm approaches the finger 20, and when brought in contact with the finger 20, moves the latter from its set position in a direction of the brake. This finger continues in its movement in this direction until the cam like portion 21 thereof contacts the pin 23, incident to which the segmental portion of the lever 12 is adjusted to separate the teeth 18 and 19 whereupon the spring functions to shift the lever 12 to normal position and the brake in contacting engagement with the flange of the turntable, thereby stopping the machine. Mounted upon the base plate 10 is a slotted lug adjustable toward and away from the latch element 14 and adapted to be positioned to limit the outward swinging movement of the latch element, the lug 26 being held fixed upon the base plate 10 by means of a set screw 27.

While it is believed that from the foregoing description the nature and advantages of the invention will be better understood, I desire to have it understood that I do not limit myself to the details herein shown and described, and that such changes may be resorted to when desired as fall within the scope of what is claimed.

What I claim is:—

1. An automatic stop for talking machines comprising a lever pivoted beneath the record table, a brake supported by said lever and normally engaging the table, a pivoted latch cooperating with said lever to maintain the brake spaced from said table, a resilient connection between said lever and latching element and a finger fitted on said latch element and adapted to be positioned in the path of movement of the tone arm of the machine, and actuated thereby to raise the lever from said latch element.

2. An automatic stop for talking machines comprising a lever pivoted beneath the record table, a brake carried by said lever and normally engaging the table, a pivoted latch element cooperating with the lever for holding the brake spaced from said table, a resilient connection between said lever and said latch element, a finger pivoted upon the latch element and adapted to be moved by said lever to a position in the

path of movement of the tone arm of the machine, whereby the finger is actuated to release the lever from said latch element.

3. An automatic stop for talking machines comprising a lever pivoted beneath the record table, a brake carried by the lever and normally engaging said table, a pivoted latch element cooperating with the lever to hold the latter in an adjusted position when the brake is spaced from said table, a spring providing a connection between the lever and said latch element, a finger pivoted upon the latch element, means on the lever for moving said finger to a set position, said latch element being influenced by said finger and moved away from the lever when the latter is moved in one direction, an adjustable stop limiting the movement of the latch element in one direction, the said finger being actuated by the tone arm of the machine to effect a release of the lever from said latch element.

4. An automatic stop for talking machines comprising a lever pivoted beneath the record table, a brake supported by the lever and normally engaging said table, a latch element pivoted adjacent the lever and cooperating therewith to hold the latter in an adjusted position and the brake spaced from the table, a resilient connection between the lever and said latch element, a finger pivoted upon the latch element, and having a cam like portion, a pin carried by the lever for moving said finger to a set position in the path of movement of the tone arm, during which time the latch element is moved away from said lever, said finger being actuated by the tone arm to effect a release of the lever from said latch element when said finger is again brought into contact with said pin.

5. An automatic stop for talking machines comprising a lever pivoted beneath the record table and having a segmental portion, a brake carried by the lever and normally contacting said table, a tooth projecting from said lever, a latch element pivoted adjacent the lever and curved to conform to the shape of the segmental portion, a tooth projecting from the latch element and adapted to engage the tooth of the lever to hold the lever in one position with the brake spaced from the table, a resilient connection between the lever and said latch element, a finger pivoted upon the latch element to move said lever to its set position in the path of movement of the tone arm of the machine, said finger being actuated by the tone arm and cooperating with means on the lever to effect a release of the latter from the latch element when the finger assumes a predetermined position.

In testimony whereof I affix my signature.
ELZA E. WIFORD.
